(57) CLAIM

The ornamental design for a sports board stand, as shown and described.

DESCRIPTION

FIG. 1 is a perspective view of a sports board stand showing my new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof; and,

FIG. 8 is a perspective view of the sports board stand in use holding a sports board shown in broken lines.

The broken lines are for illustrating environment and form no part of the claimed design. The sports board stand is fabricated of transparent material.
